CLAIM

The ornamental design for a combined table with display device as shown and described.

DESCRIPTION

FIG. 1 is a front, right, top perspective view of a combined table with display device showing our new design in a first position of use in which the display device is horizontally oriented and beneath the tabletop;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a front, right, top perspective view thereof in a second position of use in which the display device is vertically oriented to face a user so that the user can watch content on the display device;

FIG. 9 is a front view thereof;

FIG. 10 is a rear view thereof;

FIG. 11 is a left side view thereof;

FIG. 12 is a right side view thereof;

FIG. 13 is a top plan view thereof;

FIG. 14 is a bottom plan view thereof; and,

FIG. 15 is an exploded front perspective view thereof showing a table separated from a display device.

The broken lines depict portions of the Combined Table With Display Device that form no part of the claimed design.
